Primary Examiner — Ryan Harvey(74) *Attorney, Agent, or Firm* — Proi Intellectual Property US; Klaus Michael Schmid(57) **CLAIM**

The ornamental design for a trampoline, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective top View of a trampoline;

FIG. 2 is a front View thereof;

FIG. 3 is a rear View thereof;

FIG. 4 is a top View thereof;

FIG. 5 is a bottom View thereof;

FIG. 6 is a left side View thereof; and,

FIG. 7 is a right side View thereof.

1 Claim, 7 Drawing Sheets
(7 of 7 Drawing Sheet(s) Filed in Color)(56)
